PRODUCTION OF MOTOR GASOLINES

Ernest Carlton Housam and Ronald Lester, Sunbury-on-Thames, England, assignors to The British Petroleum Company Limited, London, England, a British joint-stock corporation

No Drawing. Application March 12, 1957
Serial No. 645,412

Claims priority, application Great Britain March 22, 1956

6 Claims. (Cl. 208—17)

This invention relates to the production of motor gaso-line.

2

agents such as fluorine, phosphoric acid or silica. A catalyst comprising tungsten and nickel oxides on alumina is also suitable.

According to one particular method of preparing a high octane component from an SO_2 kerosene extract, a kerosene extract having a boiling range of 170° to 260° C. is passed at 1.0 v./v./hr. of liquid feedstock over a catalyst consisting of the oxides of cobalt and molybdenum on alumina at 990° F. and 900 p.s.i.g. together with 8,000 s.c.f./b. of hydrogen. A gasoline fraction was recovered from the products of the hydrogenation step and was blended with a light catalytically cracked gasoline derived from Kuwait crude oil in the ratios of 60:40 and 55:45 by volume. The properties of the two components and of the blends are set out in the following table.

	Feed	Product		L.O.C. Gasoline	Blend 1	Blend 2
		Total	Gasoline ¹			
Kuwait kerosene SO_2 extract, percent vol.	100	100			60	55

¹ Yield of gasoline on total hydrocracked product: 87% weight.

² Figures denote iso octane plus ml.TEL/USG.

³ Calculated value.

According to the invention, a high octane motor gasoline of adequate volatility consists essentially of a blend of a high octane, low volatility component produced by catalytically destructively hydrogenating an aromatic extract derived from petroleum and boiling above the gasoline line range, and a high octane, high volatility component consisting of the lower boiling fraction of catalytically cracked gasoline having an end boiling point between 80° and 120° C.

Aromatic extracts suitable for the preparation of a blending component for use in accordance with the present invention are obtained during the solvent extraction of kerosene fractions for the production of refined kerosene, and of lubricating oil fractions in the production of lubricating oils.

The aromatic extract may be subjected to catalytic destructive hydrogenation over a wide range of conditions. In general however, the hydrogenation process is carried out at a temperature of at least 800° F., a pressure of at least 500 p.s.i.g. and with a hydrogen circulation rate of at least 4,000 s.c.f./b. The space velocity is advantageously between 0.5 and 2.0 v./v./hr. of the liquid feedstock.

Any sulphur resistant hydrogenation catalyst may be employed but the catalyst is preferably on an alumina base. The catalyst may be of cobalt and molybdenum oxides on alumina either unpromoted or promoted with

It will be seen that both blends had a Research octane number with 1.5 ml. TEL/IG of at least 100, and that whereas only 8% by volume of the gasoline derived from the extract was recovered at 100° C., at least 44% by volume was recovered at 100° C. in the case of the two blends.

We claim:

1. A high octane motor gasoline of adequate volatility, said motor gasoline having a Research octane number with 1.5 ml. TEL/IG of at least 100, a volatility of not less than about 44% volume recovered at 100° C. and consisting essentially of a blend of two components, one being a high octane, low volatility gasoline recovered from the products produced by catalytically destructively hydrogenating an aromatic extract derived from the petroleum and boiling above the gasoline range, and the other being a high octane, high volatility gasoline fraction consisting of the lower boiling fraction of catalytically cracked gasoline having an end boiling point between 80° and 120° C.

2. A gasoline according to claim 1, wherein said aromatic extract has been derived from a kerosene fraction.

3. A gasoline according to claim 1, wherein said aromatic extract has been derived from a lubricating oil fraction.

4. A gasoline according to claim 1, wherein the aro-

matic extract has been subjected to catalytic destructive hydrogenation at a temperature of at least 800° F., a pressure of at least 500 p.s.i.g., and with a hydrogen circulation rate of at least 4000 s.c.f./b.

5. A gasoline according to claim 1, wherein the catalyst employed for the destructive hydrogenation of the aromatic extract consists of the oxides of cobalt and molybdenum on alumina, promoted with an agent selected from the group consisting of fluorine, phosphoric acid and silica.

6. A gasoline according to claim 1, wherein the catalyst employed for the destructive hydrogenation of the

10

aromatic extract consists of the oxides of tungsten and nickel on alumina.
